UNITED STATES PATENT OFFICE.

WINFIELD HANCOCK YOST, OF MONTREAL, QUEBEC, CANADA, ASSIGNOR TO
NATIONAL DUMP CAR COMPANY, OF CHICAGO, ILLINOIS.

CAR-DOOR-OPERATING MECHANISM.

1,028,415.

Specification of Letters Patent.

Patented June 4, 1912.

Application filed September 30, 1910. Serial No. 584,677.

To all whom it may concern:

Be it known that I, WINFIELD HANCOCK YOST, of the city of Montreal, Province of Quebec, Canada, have invented certain new and useful Improvements in Car-Door-Operating Mechanism; and I do hereby declare that the following is a full, clear, and exact description of the same.

My invention relates particularly to door operating mechanism for dump cars and it has for its object to facilitate the operating of such discharge doors, and to improve and simplify the operating mechanism.

The invention consists of the construction, combination, and particular arrangement of parts hereinafter described and pointed out in the claims. For full comprehension, however, of my invention reference must be had to the accompanying drawings forming a part of this specification, and in which similar reference characters indicate the same parts and wherein:

Figure 1, is a transverse vertical sectional view of a car constructed according to my invention; Fig. 2 is a side elevation of one half thereof; Fig. 3 is a plan view of the underside of the car; and Fig. 4 is a similar view to Fig. 3 and drawn to a larger scale and illustrating the portion of the car dis-

closed in Fig. 2. Fig. 5 is a detail trans-

verse vertical section taken on the line 5—5

Fig. 4 and illustrating particularly the retaining bar for guiding and preventing dis-

placement of the laterally movable shaft.

In the present embodiment of my invention the car illustrated has a fixed body the floor frame whereof comprises a pair of side sills *b*, end sills *c*, longitudinal intermediate sills *d*, auxiliary sills *e* situated transversely

between the sills *d*, and side and auxiliary

sill spacers *e'*, a pair of platforms *y y'*, one

at each end and extending from the ends of

the car to the adjacent upright of the hop-

per such platform being supported by the

longitudinal sills.

The superstructure carried by this floor frame comprises inclined end hopper walls *f* and side walls consisting of vertical and inclined portions *g* and *h* respectively, the

longitudinal intermediate sills *d* and auxil-

iary sills *e* having the lower ends of these

hopper walls fastened thereto, thus forming

a door frame presenting a discharge open-

ing.

The doors, *i* and *j*, closing the discharge

opening are hinged as at *k* to the sills *d* and are provided on their underside with rails *m* presenting tread surfaces *m'*, and *m''* the latter of which, when the doors are closed, converge slightly toward supporting rails *o* suspended from the floor framing.

The doors are operated by laterally movable shafts *p* *p'* supported on the rails *o*, and acting in conjunction with such rails, the rails on the underside of the doors, and unitary gear operatively connected to both doors and comprising the following mechanism. A series of bearing brackets *r* and *r'* suspended from the sills *b* and spacers *e'* respectively, support an oscillatory shaft *s* having mounted rigidly thereon two pairs of crank arms *t t* and *u u*, respectively, the arms *u* of one pair being located at a short distance from the opposite ends of the shaft while the arms *t* of the other pair are located close to the ends. These arms *t t* are connected to the shafts *p'* by pitmen *v* extending past the ends of the doors *i* outside of the vertical planes of both doors, and the arms *u* are connected to the shaft *p* by shorter pitmen *w* extending beneath the door *i*, pins *v'* and *w'* respectively connecting pitmen *v* to arms *t* and pitmen *w* to arms *u*.

The shaft *s* is oscillated to operate the doors as will be presently set forth. The means for oscillating the shaft comprises a chain *2* passing over a chain pulley *3* rigid on the shaft, the chain being fastened to the pulley by bolts *4* to obviate any chance of slip when the doors are being operated. Chain *2* is driven from an operating shaft *5* located above the floor frame and extending longitudinally of the car from a point near the inner end of the end platform *y* to a point slightly beyond the center line of the hopper, at which center line the chain *2* is located, the shaft *5* being supported in bearings *6* on the spacer members *e'*.

Chain *2* is fastened at its ends to shaft *5* by bolts *7* and the chain is so arranged relatively to the shaft that as the doors move from open to closed position (or vice versa) one end of the chain unwinds from the shaft as the other end winds thereon. This arrangement of chain *2* is clearly illustrated in Fig. 4 of the drawings in which the doors are shown closed and one end of the chain is shown wound several times around the shaft, the number of turns being necessarily

sufficient to allow the doors to be swung to open position, in which latter position the opposite end of the chain will be wound upon the shaft. This chain pulley 3 chain 5 2 and shaft 5 afford a simple and effective means for transmitting power to the shaft *s* and simultaneously multiplying such power to facilitate the closing of the doors.

In order to prevent the shaft *p* being 10 lifted from the rail *o* by the pitman *w* during the first part of the closing operation, and also to prevent it jumping from place when it is precipitated to its seat as the doors are opened, a retaining bar *n* is connected at one end to the upright portion *o'* 15 of rail *o* and at its opposite end to the upright portion *o''* of such rail, the bar *n* diverging upwardly from the rail *o*.

Shaft 5 is operated by a lever 10 loosely 20 mounted on the end thereof adjacent to the platform and adapted to be operated therefrom, this lever carrying a pawl 11, which engages a ratchet wheel 12 rigid on the shaft 5. To lock the shaft *s* against reverse 25 movement when the doors are being closed a detent pawl 13 mounted on the bearing strap *r* and engaging a ratchet wheel 14 rigid on the shaft is provided.

The mechanism and particular arrangement thereof above described enables the doors to be operated from the car which is especially advantageous when the car is being unloaded from trestles or the like, while the operating parts are simple in construction 30 and easily renewed in case of breakage.

Operation: To move the doors from open position (shown in dotted lines in Fig. 1) to closed position (shown in full lines in the same figure) lever 10 is operated rotating shaft 5 in the direction shown by the arrow 25. As shaft 5 is rotated the shaft *s* is caused to rotate in the same direction by the chain 2, one end of the latter being wound upon shaft 5 and the other end unwound therefrom. The arms *t* and *u* are thereby swung to the position shown in full lines (Fig. 1) causing the shafts *p* and *p'* to travel up the rails *o* and bear against the tread surfaces *m' m'* of the rails on the underside of the doors thus lifting the doors to within close proximity of the door frame, and as the shafts continue upward they become wedged between the upper ends of the rails *o* and the converging portions *m''* of the rails *m* thus tightly closing and locking the doors. To open the doors shaft 5 is rotated in an opposite direction with a corresponding reverse rotation of shaft *s*, and reverse movement of the arms *t* and *u*, until the shafts *p* and *p'* clear the portions *m''* thus releasing such shafts and permitting them 55 60

and the doors to fall to full open position. The bar *n* corrects any tendency of the shaft *p* to be displaced from its seat at the angle of the rail *o* and its upright *o'* while the divergence of the bar from the rail *o* permits the entry of the shaft to position. 65

What I claim is as follows:—

1. In a car, the combination with door operating mechanism including an oscillatory shaft, of means for oscillating such shaft comprising a chain pulley rigid on said shaft, a chain looped intermediate its ends over such chain pulley, a second shaft to which the ends of the chain are secured, and means for rotating the second shaft. 70

2. A dump car having an end platform, a door frame presenting a discharge opening spaced longitudinally of the car from the said platform, a door hinged to the door frame to swing transversely of the car, a shaft extending longitudinally of the car at one side of the said opening and terminating at opposite ends at points adjacent the ends of the said opening, means operatively connecting the said shaft and door, a second shaft arranged longitudinally of the car above the first mentioned shaft and having one end thereof extending beyond the corresponding end of the first mentioned shaft 80 to a point adjacent the said platform, means for operating the last mentioned shaft, and means operatively connecting the said shafts together. 85

3. A dump car having an end platform, a door frame presenting a longitudinally disposed discharge opening spaced longitudinally of the car from the said platform, a pair of doors hinged to the opposite sides of the door frame, a shaft extending longitudinally of the car at one side of the said opening and terminating at opposite ends at points adjacent the ends of the said opening, means operatively connecting the shaft to each of the doors, a chain pulley upon such shaft, a second shaft arranged longitudinally of the car above the first mentioned shaft and having one end thereof extending beyond the corresponding end of the first mentioned shaft to a point adjacent the said platform, a chain passing over the said pulley and connected to the said second shaft, and an operating lever upon the end of the said second shaft adjacent the said platform. 105 110 115

In testimony whereof, I have signed my name to this specification, in the presence of two subscribing witnesses.
